UNITED STATES PATENT OFFICE.

GEORGE S. HILL, OF STRAFFORD, NEW HAMPSHIRE, ASSIGNOR TO UNITED SHOE MACHINERY COMPANY, OF PATERSON, NEW JERSEY, A CORPORATION OF NEW JERSEY.

STOPPING MECHANISM.

1,181,766.

Specification of Letters Patent.

Patented May 2, 1916.

Application filed April 27, 1914. Serial No. 834,720.

To all whom it may concern:

Be it known that I, GEORGE S. HILL, a citizen of the United States, residing at Strafford, in the county of Strafford and State of New Hampshire, have invented certain new and useful Improvements in Stopping Mechanism; and I do hereby declare the following to be a full, clear, and exact description of the invention, such as will enable others skilled in the art to which it appertains to make and use the same.

The invention relates to stopping mechanism for button-hole sewing or other machines in which the machine or some mechanism of the machine is to be stopped in predetermined position.

The object of the invention is to provide novel and improved means for throwing out the stopping mechanism when for any reason it is desired to turn the driving shaft by hand, and for preventing the throwing in of the driving mechanism until the parts are again restored to their normal condition.

To these ends the invention consists in the features of construction and combinations of parts hereinafter described and referred to in the claims.

The features of the invention will be readily understood from an inspection of the accompanying drawings and the following detailed description of the mechanism illustrated therein.

In the drawings, Figure 1 is a front elevation showing so much of a buttonhole sewing machine as is necessary to illustrate the application of the invention thereto; Fig. 2 is a detail sectional view showing the parts in stopping position; Fig. 3 is a similar view showing the position of the parts when the driving shaft has been turned manually through a partial revolution; Fig. 4 is a plan view showing the parts for rendering the stopping devices and the automatic starting devices inactive in normal position; Fig. 5 is a similar view showing the parts in a position corresponding to Fig. 3; Fig. 6 is a plan view of the driving and stopping mechanism; Figs. 7, 8 and 9 are details of the devices for engaging and disengaging the driving clutch, and Fig. 10 is a detail vertical sectional view of the parts shown in Figs. 2 and 4.

In the drawings the invention is shown embodied in a buttonhole sewing machine having the general construction and mode

of operation of the machine shown and described in Patent No. 1,063,880, June 3, 1913. In this machine the stitch forming mechanism and the mechanism for feeding the work clamp are driven during the sewing of the buttonhole from a driving shaft 2. The mechanism for driving and stopping the shaft comprises a continuously rotating driving pulley 4 which is loosely mounted on a sleeve 6 surrounding the shaft. The pulley is provided with an internal clutch face adapted to coöperate with a clutch disk 8 which is fast to the shaft. The pulley is forced in a direction to engage the clutch members by a spring 10 interposed between the end of the sleeve 6 and a knurled head 12 secured to the end of the shaft. The pulley is moved against the tension of the spring to disengage the clutch members through pins 14 which pass through the hub of the clutch disk 8 and are interposed between the end of the sleeve 6 and a bearing plate 16 which loosely surrounds a sleeve 18. A ball bearing 20 is interposed between the disk 16 and the end of a clutch actuating sleeve 22 which is mounted to turn loosely on the sleeve 18. The sleeve 22 is provided with two cam segments 24 arranged to coöperate with cam segments 26 formed on a stationary disk 28 in moving the driving pulley against the tension of the spring 10 to disengage the clutch members, and in allowing the pulley to be moved in the opposite direction by the spring to engage the clutch members. The cam sleeve 22 is rocked in a direction to disengage the clutch members by a rack 30 formed on the upper end of a vertically movable bar 32, the lower end of which rides on a cam rib 34 secured to the upper face of the cam carrying gear 36. When the bar 32 rides up on to the cam rib, the cam sleeve 22 is rocked so that the cams 24 and 26 force the sleeve in a direction to disengage the clutch members. When the bar rides off of the cam rib, the sleeve is allowed to rock in the opposite direction so that the spring 10 engages the clutch members.

When the members of the driving clutch are disengaged, the shaft 2 is stopped in a predetermined position by a stop arm 38 carrying a stud 40 which coöperates with a stop cam 42 connected with the clutch disk 8. The stop cam is mounted on the hub of the clutch disk 8, and is connected therewith by a pin 44 which passes through a

segmental slot formed in the clutch disk, and is engaged by one end of a spring 46, the other end of which bears against a lug 48 on the clutch disk.

- 5 The stop arm 38 is secured to a vertical rock shaft 50, and is connected with a spring 52 which yieldingly supports the arm in position with the upper end of the shaft against a stop screw 54, and also tends 10 to swing the arm in a direction to bring its stud 40 into the path of the stop cam 42. When the clutch members are in engagement, the stop arm is held out of the path of the cam 42 against the tension of the spring 15 52 by a cam 55 on the carrying gear 36 which engages an arm 56 on the lower end of the shaft 50. The cams 34 and 55 are so arranged that when the clutch members are disengaged the arm 56 is released so that 20 the spring 52 may swing the stop arm into active position and bring its stud 40 into the path of the cam 42. At this time the stop 40 rides along the inclined side 58 of the cam, so that the stud moves gradually 25 into the path of the cam. After the clutch members have been disengaged, the rotation of the shaft 2 continues under the inertia of the parts, and the end of the stud 40 rides over the braking portion 60 of the 30 cam 42, which depresses the stop arm against the tension of the spring 52, thus gradually overcoming the momentum of the parts. As the end of the stud rides off the portion 60 of the cam, it is engaged by 35 the abrupt rise 62, so that the shaft 2 is brought to rest with the end of the stud in the low part or depression between the braking portion 60 and the stopping portion 62 of the cam, as indicated in Fig. 2. When 40 the stop arm swings into active position, the stud 40 rides against a wear plate 64 which is secured to the rear face of the cam 42 and acts to accurately position the stud with relation to the cam.
- 45 In order that the stopping mechanism may operate in the most efficient manner, and with the minimum shock and jar, it is desirable that the point in the rotation of the shaft at which the clutch members 50 are disengaged should be varied in accordance with the speed at which the machine is being driven. If the speed increases at any time during the operation of the machine, the clutch members should be disengaged earlier in the rotation of the shaft, in order that the momentum of the parts may be properly overcome before the shaft reaches the stopping position. If the speed decreases, on the other hand, the clutch 55 members should be disengaged later, in order that the parts may be brought to stopping position by the momentum of the parts. Means is accordingly provided by 60 which the operator may quickly and conveniently vary the timing of the clutch dis-

engaging devices. In the construction shown, this is accomplished by forming worm teeth on the periphery of the stationary cam disk 28, which are engaged by a worm 66 secured on a shaft 68. The shaft 70 is provided with a knurled head 70 which is in position where it may be conveniently manipulated by the operator during the running of the machine, in case it is found desirable to vary the timing of the disengagement of the clutch by reason of any variation in the speed of the driving mechanism through which the machine is driven.

In the buttonhole sewing machine illustrated the stopping devices are so arranged 80 that the shaft 2 is brought to rest when the needles of the stitch forming mechanism are retracted, the under needle being withdrawn below the work clamp where it is not conveniently accessible to the operator. In order that the under needle may be rendered conveniently accessible, as, for instance, when it is to be threaded, it is desirable that provision be made for turning the shaft 2 through at least a partial revolution by 85 hand. To enable this to be conveniently done, devices are provided by which the operator may render the stopping devices inactive, and in order that injury to the machine may not result from failure to restore 90 the parts to their normal position before starting the machine, these devices include means for preventing the engagement of the driving clutch members until the devices are returned to normal position. 109

In the construction shown the means for rendering the stopping devices inactive and preventing the engagement of the driving clutch members comprise a bell crank lever, one arm 72 of which extends into position 105 where it is within convenient reach of the operator, and the other arm 74 of which is provided with a cam 76 for engaging the end of the stop arm 38 and swinging it into inactive position. The arm 74 of the lever 110 is also provided with a projection 78 which is brought into the path of a stop shoulder 80 when the lever is operated to move the stop arm 38 out of active position. The stop shoulder 80 is formed on a flange of the 115 clutch disk 8, and this flange is also provided with a recess 82 and a locking surface 84 extending from the recess to the stop shoulder. The recess is in position to receive the projection 78 on the arm 74 when 120 the parts are in stopping position, as indicated in Fig. 2. If the shaft is turned from stopping position after the bell crank lever has been swung into position to bring the projection 78 into the recess 82, then the 125 locking surface 84 engages the projection 78 and prevents the return of the bell crank lever to normal inactive position until the shaft has been returned to its normal stopping position. 120

The hub of the bell crank lever is provided with a support 86 and recess 88 arranged to coöperate with a supporting block 90 which is secured to the clutch operating rack bar 32. The block 90 is provided with a projection 92 arranged to register with the recess 88 and with a recess 94 arranged to register with the support 86 when the bell crank lever is in normal inactive position, Fig. 2. When the lever is moved into the position indicated in Fig. 3 to throw the stop arm out of active position, the support 86 is moved under the projection 92 so that it acts to support the rack bar in case the supporting cam rib 32 should pass from under the bar, and prevents the engagement of the members of the driving clutch until the bell crank lever and the stop arm are returned to their normal position. If the machine should be started, therefore, without the return of the devices to their normal position, the cam gear 36 would be driven until it reached the point at which under normal positions the driving clutch for the shaft 2 would be engaged to continue the movement of the gear and to start the sewing mechanism, and then the machine would stop, thus avoiding any injury to the various mechanisms of the machine, and indicating to the operator that the devices for throwing out the stopping mechanism and for insuring the return of the shaft to normal stopping position had not been thrown out of action before the machine was started.

While it is preferred to employ the specific construction and arrangement of parts shown and described in applying the invention to the machine illustrated in the drawings, it will be understood that the invention is not confined in its application to this machine, and that the construction and arrangement of the parts may be varied and modified as may be found desirable or best suited to the construction of the machine in which it is to be embodied.

Having explained the nature and object of the invention, and specifically described one form of mechanism in which it may be embodied, what is claimed is:—

1. A machine of the class described, having, in combination, a driving shaft, driving mechanism therefor, devices for stopping the shaft in a predetermined position when the driving mechanism is thrown out, means whereby the operator may render the stopping devices inactive to enable the shaft to be turned by hand, and means for prevent-

ing the throwing in of the driving mechanism while the stopping devices remain inactive.

2. A machine of the class described, having, in combination, a driving shaft, driving mechanism therefor, devices for stopping the shaft in a predetermined position when the driving mechanism is thrown out, and devices under the control of the operator for rendering the stopping devices inactive to enable the shaft to be turned by hand and for preventing the throwing in of the driving mechanism.

3. A machine of the class described, having, in combination, a shaft, driving mechanism therefor, stopping devices for arresting the shaft in predetermined position, means under the control of the operator for rendering the stopping devices inactive and for limiting the movement which may be given to the shaft by hand, and means for preventing the throwing in of the driving mechanism while said operator controlled means is out of its original position.

4. A machine of the class described, having, in combination, a shaft, a driving clutch, mechanism for engaging and disengaging the clutch, stepping devices for arresting the shaft in a predetermined position when the clutch is disengaged including a stop arm, a manually operated cam for moving the stop arm out of active position, and means connected with the cam for preventing the engagement of the clutch.

5. A machine of the class described, having, in combination, a shaft, devices for stopping the shaft in a predetermined position including a stop cam and a spring pressed stop member, an operating cam for moving said member out of the path of the stop cam, and a wear plate connected to the side of the stop cam against which the member rides when released by its operating cam.

6. A machine of the class described, having, in combination, a shaft, a clutch member secured to the shaft, a stop cam connected with the clutch member, a wear disk secured to the side of the stop cam, a stop arm having a stud for engaging the stop cam, a spring for forcing the stud against the wear disk, and an operating gear for moving the arm and stud out of the path of the stop cam.
